SAFETY CIGARETTE ASH TRAY

James M. Morita, Honolulu, Territory of Hawaii

Application June 5, 1953, Serial No. 359,878

3 Claims. (Cl. 131—240)

This invention relates to an ash tray for use by smokers of cigarettes, and one of the objects of the invention is to provide an ash tray with means for advancing the cigarette toward the pit of the ash tray, as the cigarette burns, so as to prevent a burning cigarette from falling out of the tray and burning furniture or starting a fire, this means being automatic in operation and responsive to the heat of the burning cigarette.

Another object of the invention is to provide a thermostatic element which is directly exposed to the heat of the burning end of a cigarette when the cigarette is laid in a grooved rest or support on the ash tray, and which will expand in such manner that the cigarette is moved inwardly on the grooved rest, so that in no case will the cigarette fall by gravity alone out of the tray, to expose furniture to scorching or combustible material to burning.

A further object of the invention is to provide a rotatable wheel with a helical thermostatic element, so arranged in a groove of the wheel, that the wheel will be caused to turn when a portion or a series of coils of the thermostatic element expands, and the expansion of the thermostatic element will propel the cigarette inwardly to prevent the outer end portion thereof from dropping from the outer portion of the ash tray.

A still further object of the invention is to provide an ash tray with a thermostatic element for propelling a burning cigarette inwardly of the tray, and a support for the element which will automatically restore the same to its initial position.

Other objects and advantages of the invention will become apparent from the following description taken in conjunction with the accompanying drawing, in which

Figure 1 is a plan view of an ash tray according to the present invention;

Figure 2 is an enlarged sectional view taken on the line 2—2 of Figure 1 illustrating the wheel at the start of its rotational travel;

Figure 3 is a sectional view taken on the line 3—3 of Figure 2 with the cigarette omitted; and

Figure 4 is a sectional view of the assembly of Figure 2, but showing the wheel adjacent the terminating point of its rotational travel.

Referring to the drawings, the numeral 1 designates an ash tray which includes an ash pit 2, and cigarette supporting rests 3, each of which is formed with a longitudinal groove 4 in which a cigarette may be placed. The groove 4 is slightly tilted from the outer end inwardly and downwardly and has its longitudinal axis in the same plane as the central vertical plane of the wheel 10.

The wall 5 of the ash tray 1 is provided with a socket 6 adjacent each of the rests 3, and in each of the sockets 6 is mounted a thermostatic cigarette propelling means 7. Since each of such means are identical, only one will be specifically described. The means 7 comprises a wheel 10 which is freely rotatable about a horizontal axis or shaft 11, the shaft being supported in the walls of the socket 6. The wheel 10 is provided with a groove 12 extending about its periphery, and in such groove rests a thermostatic helix 13, one end or the end 14 of the helix being anchored in the bottom of the socket 6, as clearly shown in Figure 2. The other end or the end 15 of the helix 13 is secured to a lug 17, Figures 2 and

2

3, projecting from the base of the groove 12. The wheel 10 is provided with an eccentrically disposed weight 18 which is preferably positioned adjacent the upper portion thereof, as shown in Figure 2. Supported in the groove 4 of the rest 3 is a lighted cigarette 19, the lighted end facing toward and overlying the helix 13. Facing the socket 6 and secured to the wall 5 of the tray 1 is a guard preferably in the form of an arcuate plate 20.

10 In operation of the ash tray according to the present invention with the lighted cigarette 19 supported on the rest 3 of the ash tray, as shown in Figure 2, heat from the lighted end of the cigarette causes the adjacent portion of the helix 13 to expand and with such expansion the wheel 10 is rotated in a clock-wise direction against the action of the weight 18 for a portion of its travel, resulting in movement of the cigarette toward the ash pit 2 of the ash tray 1 in the direction of the arrow shown in the upper portion of Fig. 4. It is to be noted that radial expansion of the helix 13 also takes place. However, the space between the guard plate 20 and the outer periphery of the wheel 10 is sufficient to permit the radial expansion without having the helix strike the upper edge of the guard plate 20. This movement of the cigarette continues as long as there is a portion of the cigarette in contact with the helix. With the removal of the lighted cigarette from engagement of the spring as by its falling into the ash pit 2, the helix cools and with such cooling the wheel is rotated in the reverse direction until the wheel is again at its starting position or that of Figure 2. Of course, most of the ashes as they fall from the lighted end of the cigarette 19 are deflected by the guard plate 20 into the ash pit 2 of the tray 1.

What is claimed is:

1. An ash tray having an ash pit and a rest mounted above and outwardly of the ash pit, a wheel positioned below said rest and adjacent said rest and rotatable about a horizontal axis, a thermostatic helix supported on said wheel in such a position so that the central vertical plane of the wheel is coplanar with the longitudinal axis of said rest and having one end anchored to said tray and having the other end secured to said wheel at a point on the periphery of the wheel substantially opposite from said one end anchored to said tray.

2. An ash tray having an ash pit and a rest mounted above and outwardly of the rest, a wheel positioned below said rest and adjacent said ash pit and rotatable about a horizontal axis, a thermostatic helix supported on said wheel in such a position so that the central vertical plane of the wheel is coplanar with the longitudinal axis of said rest and having one end anchored to said tray and having the other end secured to said wheel at a point on the periphery of the wheel substantially opposite from said one end anchored to said tray, and a weight eccentrically disposed on and carried by said wheel.

3. An ash tray having an ash pit and a rest mounted above and outwardly of the rest, a wheel positioned below said rest and adjacent said ash pit and rotatable about a horizontal axis, a thermostatic helix supported on said wheel in such a position so that the central vertical plane of the wheel is coplanar with the longitudinal axis of said rest and having one end anchored to said tray and having the other end secured to said wheel at a point on the periphery of the wheel substantially opposite from said one end anchored to said tray, and a guard plate disposed over the portion of said wheel adjacent the ash pit to deflect ash from a burning cigarette into the ash pit.
